UNITED STATES PATENT OFFICE.

FRANK M. McMAHON, OF SOUTH CANADIAN, INDIAN TERRITORY, ASSIGNOR
OF ONE-HALF TO JOHN T. LOWREY, OF SAME PLACE.

BUGGY-TOP SUPPORT.

SPECIFICATION forming part of Letters Patent No. 534,907, dated February 26, 1895.

Application filed September 8, 1894. Serial No. 522,495. (No model.)

To all whom it may concern:

Be it known that I, FRANK M. McMAHON, a citizen of the United States, residing at South Canadian, in the Choctaw Nation, Indian Territory, have invented a new and useful Improvement in Buggy-Top Supports, of which the following specification, taken in connection with the accompanying drawings, is a full, clear, and exact description.

10 My invention relates to an improved spring support for folding vehicle tops, and the object of my invention is to simplify and improve the construction of said supports.

I will first describe my invention with reference to the accompanying drawings and afterward particularly point out the novelty in the annexed claims.

In said drawings, Figure 1 is a detail side elevation representing my improved spring support attached to a buggy and showing the position it assumes when the top is lowered onto the support. Fig. 2 is a perspective view showing all of the parts of the support detached.

25 1 is the buggy body, and 2 are the bows of the top which are pivotally mounted on the body at 3, and supported in elevated position as shown in dotted lines in Fig. 1 by the customary hinged brace 4 which is pivoted at 30 top to the central bow 2 and at bottom to the prop bolt 5 which extends out from the body rail 6.

Mounted upon the squared bolt 5 is a cylindrical block 7 having a square opening 8 passing longitudinally through it for the reception of the bolt 5.

9 is a circular plate mounted on the bolt 5 inside of the block 7 and formed with a series of perforations 9^a near its periphery.

40 10 is a ring mounted upon the block 7. 11 is a double spring arm provided with a friction roller 12 on its outer loop end, and having the spring coils 13 formed on its inner ends. At the end of each of the coils 13 is a crook portion 14 for the purpose which will presently appear. The spring arm 11 and coils 13 are formed of a single piece of stout steel wire. The coils 13 are adapted to surround the block 7 on the opposite sides of 45 ring 10.

50 15 is a washer adapted to fit on the end of

the bolt 5 against the outer end of the block 7, and 16 is a plate formed with a central square opening 17 adapted to fit over the reduced squared end 18 of the bolt 5 close up 55 against the washer 15.

19 is a rod secured in the plate 16 and adapted to project parallel with the bolt 5 and engage in any one of the perforations 9^a of the plate 9. The rod 18 engages the crooked 60 ends 14 of coils 13 for holding the spring in proper position.

20 is a screw nut engaging the threaded end 21 of the bolt 5 for confining the several parts in position.

65

22 is a rod formed with the eyes 23 at its opposite ends by which it is secured to the rear bow 2 of the folding top, and adapted to engage the friction roller 12 on the spring arm 11 and confine it so that it will operate 70 up and down on said bow. One of these supports should be supplied at each side of the buggy.

The operation of my improved support will be clear from the above description, but will 75 be further explained in a few words.

When the top is elevated as shown in dotted lines in Fig. 1, the brace 4 will hold it in this position, my improved spring support turning on the block 7 and assuming the position shown in dotted lines; but when the top is folded into lowered position, as shown in full lines in Fig. 1, the friction roller 12 travels on the edge of the rear bow 2 within the elongated slot or loop formed by the guide 80 rod 22, and supports the top in that position.

The support has proven very efficient and prevents the bending or breaking of the top bows, or their pivot bolts, and injury to the buggy body or other parts, which is likely to 85 be caused in the old forms of supports by severe jolting over rough roads, while the preponderance of weight of the top rests on the prop bolts. Besides being efficient my support is simple and economical. The elevation 90 of the support can be regulated by removing the nut 20 and adjusting the rod 19 to any one of the holes 9^a.

Having thus described my invention, the following is what I claim as new therein and 95 desire to secure by Letters Patent:

1. The combination of a folding vehicle top,

- a guide rod secured to one of the top bows, and forming an elongated slot or loop, an adjustable spring supported arm mounted upon the vehicle body and projecting over into
- 5 proximity to the top bow, and a flanged friction roller mounted on said spring supported arm and engaging the bow and confined in the elongated slot or loop formed by the guide rod, substantially as set forth.
- 10 2. The combination of a folding vehicle top, with a spring support and prop, comprising a prop bolt extending out from the vehicle body, a spring arm mounted on the prop bolt, and an adjustable rod 19 engaging the spring
- 15 ends of the arm, substantially as set forth.
3. The combination of a folding vehicle top,

with a spring support and prop comprising a prop bolt extending out from the vehicle body, a plate secured to said bolt and formed with a series of perforations adjacent to its 20 periphery a block mounted on said bolt, a spring arm formed with coil spring extensions which are mounted on said block, and a plate secured on the end of the prop bolt and carrying a rod which engages the ends of the 25 spring coil extensions for holding them, and fits in one of the perforations of the plate, substantially as set forth.

FRANK M. McMAHON.
